HANDLE FOR FLOWERPOTS AND THE LIKE

Rollin C. Skinner, Loveland, Colo.

Application April 2, 1935, Serial No. 14,207

2 Claims. (Cl. 215—100)

This invention relates to a handle construction and has for its principal object the provision of a handle which can be applied to tin cans, flower pots, etc. to form an ornamental, convenient, 5 plant hanger and support.

Another object of the invention is to so construct the handle that it can be rigidly attached to a tin can or other sheet metal container so as to form a substantial and permanent handle 10 thereon.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the 20 drawing and throughout the description.

In the drawing:—

Fig. 1 illustrates the preferred form of the invention.

Fig. 2 illustrates an adaptation of the preferred 25 form.

Fig. 3 illustrates an alternate form of the invention.

Fig. 4 illustrates a tin can flower container prepared for delivery from a flower shop by the 30 use of this invention.

The invention comprises a metallic strip 10 bent in a U-shape having any desired artistic contour. The strip is preferably twisted as illustrated, to add to the ornamental appearance and increase the rigidity thereof.

The free extremities of the strip 10 are turned outwardly and cut on a bevel to form pointed extremities 11. The two pointed extremities are 40 secured to an annular band or ring 12. The handle as described is applicable to attachment to tin cans or other sheet metal containers and to the usual flower pots.

A typical flower pot is illustrated at 13, with its 45 rim flange at 14. A typical tin can container is illustrated at 15. In applying the invention to a flower pot, the latter is simply set within the ring 12, allowing the latter to act as a support beneath the rim flange 14. It is preferred to form the handle strip 10 so that it will

clamp against the sides of the rim flange to securely hold the pot in place in the ring.

When applied to a tin can such as at 15, the ring portion is slipped inside the can, and the sharpened extremities 11 are forced outwardly 5 through the can metal and preferably bent upwardly on the exterior thereof. This forms a rigid permanent attachment to the can, and allows the latter to be used for hanging or transporting flowers. The handle portion is 10 sufficiently large to surround the usual plant, and serves as a convenient handle for transporting or hanging the plant.

The device is capable of variations, for instance, in Fig. 2, a variation is illustrated in 15 which the sharpened extremities 11 have been removed, and the latter is used simply for supporting flower pots. Fig. 3 illustrates an adaptation in which the ring 12 has been removed, and the device is attached entirely by the turned- 20 up pointed extremities 11.

The invention is particularly valuable for florist shops as it enables inexpensive tin cans to be used as ornamental containers for flowers. These can be covered with ornamental paper 25 sheets, which in combination with the handle 10 form an inexpensive, yet ornamental method of delivering flowers, such as is illustrated in Fig. 4.

While a specific form of the improvement has been described and illustrated herein, it is desired 30 to be understood that the same may be varied, within the scope of the appended claims, without departing from the spirit of the invention.

Having thus described the invention, what is claimed and desired secured by Letters Patent 35 is:—

1. A handle for containers comprising: a U-shaped metallic band; outwardly turned, pointed extremities on said band; and a metallic ring connecting the free extremities of said band 40 above said pointed extremities.

2. A handle for attachment to containers to form flower holders comprising: an annular band; a U-shaped handle member extending upwardly from said band, the lower extremities of 45 said handle member passing through and being enclosed by said band; and outwardly turned points formed on said lower extremities so that they may be forced through the wall of a container.
